UNITED STATES PATENT OFFICE

WILLIAM L. DAYTON, OF FORT WORTH, TEXAS, ASSIGNOR OF ONE-HALF TO JOHN M. SCOTT, OF FORT WORTH, TEXAS

AIR COMPRESSOR

Refile of abandoned application Serial No. 202,067, filed June 28, 1927. This application filed October 23, 1928. Serial No. 314,394.

My invention relates to compressors and more particularly to double compressors and means to conserve the power usually lost in the operation of compressors; and the object is to provide simple power jacks which may be used as single power jacks or double power jacks in operating compressors. An advantage of this construction and arrangement hereinafter shown is that the engine or motive power is approximately doubled by use of weights and levers hereinafter explained. Other objects and advantages will be more particularly pointed out in the claims.

Reference is had to the accompanying drawings which form a part of this application.

Fig. 1 is a side elevation of a double air compressor.

Fig. 2 is an end elevation of the same, with storage tank omitted.

Fig. 3 is a plan view of the same, showing the storage tank.

Fig. 4 is a side elevation of a compressor which is a variation of the compressor by substituting a compressing mechanism for the weight shown in the previous views.

Fig. 5 is an end elevation of the same.

Fig. 6 is a plan view of the same.

Fig. 7 is a side elevation of a compressor which is a variation of the device shown in Figs. 4 to 6 inclusive.

Fig. 8 is an end elevation of the same.

Fig. 9 is a plan view of the same.

Fig. 10 is a side elevation of a single compressor, such as one of the compressors shown in Figs. 1 to 3 inclusive.

Fig. 11 is an end elevation of the same.

Fig. 12 is a plan view of the same.

Similar characters of reference are used to indicate the same parts throughout the several views.

The air compressor shown in Figs. 1 to 3 inclusive has two walking beams 1 and 2 and stationary fulcrums 3 and 4. Normally the walking beams 1 and 2 are fulcrumed in the supports 3 and 4 respectively. Means is provided for actuating the walking beams 1 and 2. A combined fly-wheel and power wheel 4' is provided with a shaft 5 which is jour-

naled in bearing means 6 provided for the shaft 5. The wheel 4' is driven by a motor 7 which is provided with a drive pulley 8 which drives the power wheel 4' by means of a belt 9. The walking beam 1 is connected to the power wheel 4' by means of a crank 10 which is pivotally connected to a link bar 11. Two bars 12 are attached rigidly to the beam 1 and the link bar 11 is caught in between the ends of the bars 12 and pivotally connected to the bars 12, the object being to pivot the link bar 11 on the walking beam 1.

The walking beam 2 is connected to the power wheel 4' in a similar manner. Bars 12 are rigid with the walking beam 2. A link bar 13 is pivotally connected to the bars 12 and the link bar 13 is pivotally connected to a crank 14. The beams 1 and 2 may be strengthened by truss rods 15 which are attached to the bars 12 and to collars 16 which are rigidly connected to the walking beams.

The drawings show compressor cylinders 17-18 which are made with the lower parts 17 larger in diameter than the upper parts 18. The compressed air cylinders are provided with pistons and piston rods 19 which are pivotally connected to link bars 20 which are pivotally connected to the beams 1 and 2. The walking beams 1 and 2, Figs. 1 and 10, are provided with weights 21. Pipes 22 and 23 and 24 connect the cylinders 17 with a storage tank 25.

In operation, the motor 7 drives the gearing which actuates the walking beams 1 and 2. On the down stroke of a walking beam, the air is compressed in a cylinder 17. The motor is driving the wheel 4'. On the upstroke of the same walking beam, there will be no loss of power because the weight 21 will balance all the weight of the mechanism on the other side of the fulcrum 3. The walking beam 2 operates in precisely the same manner and one mechanism does not hinder the other. The two mechanisms secure double the amount of compressed air in the tank 25 as one would secure.

The walking beam 26 of the compressor shown in Figs. 10 to 12 inclusive operates in precisely the same manner as one of the walking beams shown in Figs. 1 to 3 inclusive.

In all the forms of this invention, there is a power wheel 4'. In Figs. 7 to 12 inclusive, a fly wheel 27 co-operates with the power wheel 4'. In Figs. 4 to 6 inclusive, pump 28 takes the place of the weights 21 of the other forms of invention. The compression in the pump cylinders 28 takes the place of the weight 21 which is approximately one thousand pounds. The compression in pump 28 10 resists the load just as the weight 21 resists the load. The pumps 28 are mounted on stands or supports 29 and the pistons for the pumps 28 are actuated by the bars 30' which are pivotally connected to the walking beams 15 1 and 2 and pivotally connected to vertical bars 31 which engage cross bars 32 which actuate the piston rods of the pistons. The link bars 31 and the cross bar 32 (operating) in slot 29' of support 29 constitute a yoke. 20 Figs. 7 to 9 inclusive show means for increasing the power of the walking beams 1 and 2. The devices shown in these views show a slight variation from the devices shown in Figs. 4 to 6 inclusive. The tank 25 25 is shown in a different position. The fly-wheel 27 is in the same position, but the band wheel 4' is located in a different position but is driven in the same manner. A cog wheel 36 is rigid with the shaft of wheel 4' and this cog wheel 36 meshes with and drives a pinion 40 which is rigid with the shaft 39 of fly-wheel 27 and drives this shaft. The fly-wheel 27 in this variation is a driven fly-wheel. Levers 33 are pivotally connected to the ful- 35 crums 3 and 4 by pivot bolts 35 and pivotally connected to link bars 11 which are connected to the cranks 10. The levers 33 are pivotally connected to the beams 1 and 2 by means of link bars 37 and bolts 38. 40 In all the forms of the power jacks above set forth, the same stationary fulcrums in members 3 and 4 are used, and the same connection of the walking beam between its power end and the stationary fulcrum is 45 used for temporarily shifting the stationary fulcrum of the walking beam to a movable fulcrum and means are provided for increasing the power of the walking beam on the piston of the compressing cylinder, such 50 means being the weight 21 and the variations in the levers 33 and gear 36 and the fulcrum 35 and shaft 39, and the pump 28 and its mechanism. 55 In the forms of compressor shown in Figs. 4 to 9 inclusive, compressed air is taken from the lower parts of the cylinders 17 and compressed air is taken from the upper parts of cylinders 28 by means of pipes 22, 23, and 24. Considering Figs. 4 and 6, the piston in cylinder 17 on the lower side of Fig. 6 is compressing downwardly and the piston in cylinder 28 on the lower side of Fig. 6 is compressing upwardly. At the same time the piston in cylinder 17 on the upperside of Fig. 65 6 is going upwardly for a charge and that in

cylinder 28 on the upperside is going downwardly for a charge. On the upper side of the Fig. 6, the cylinders operate in the same manner but alternately relative to the cylinders on the lower side of Fig. 6. 70

This application is made to revive the invention set forth in the application filed by me on June 28, 1927, Ser. No. 202,067 and abandoned. 75

What I claim is.

1. In a compressor, the combination of a walking beam having a power end and a work end, a stationary fulcrum, a power wheel operatively connected to the power end of said walking beam, a compressing cylinder provided with a piston rod, means for cooperating with said power wheel for exerting power on said walking beam consisting of link bars pivotally connected to said walking beam between the power end thereof and said stationary fulcrum and connected to the piston rod and means including an inverted air compressing cylinder and a piston therefor operatively connected to the opposite end of said walking beam and co-operating with said power wheel to increase the work accomplished by the compressor. 80

2. In a compressor the combination of a walking beam having a power end and means for applying power thereto, a stationary fulcrum therefor, a compressor cylinder having a plunger operatively connected to said walking beam between said fulcrum and power end, a compressor cylinder on the opposite side of said stationary fulcrum provided with a plunger, and link bars operatively connecting said plunger to said walking beam and adapting said compressor to compress on the upstroke of its plunger simultaneously with the compressing of the said first named compressor on the downstroke of its plunger. 90 100

3. In a compressor, the combination of a fly-wheel and a power wheel, a walking beam and a stationary fulcrum therefor, a link bar operatively connecting said power wheel and the power end of said walking beam, a compressing cylinder, means between the power end of said walking beam and said fulcrum operatively connecting said beam to said compressing cylinder, and a power absorbing element operatively connected to the opposite end of said walking beam and compressing on the upstroke. 110 115

4. In a compressor, the combination of a fly-wheel and a power wheel, a walking beam and a stationary fulcrum therefor, means for driving said power wheel, a link bar operatively connecting said power wheel to the power end of said walking beam, a compressing cylinder, means between the power end of said beam and said fulcrum operatively connecting said beam to said compressing cylinder, and power absorbing means on the opposite end of said walking beam operated by said power wheel. 120 125 130

5. In a compressor, the combination of a fly-wheel and a power wheel, a walking beam and a stationary fulcrum therefor, means for driving said power wheel, a crank and a link bar operatively connecting said power wheel and said walking beam, a compressing cylinder provided with a piston rod and plunger, means for applying power to said piston rod consisting of link bars connected to said walking beam between the power end and said stationary fulcrum and connected to said piston rod, and power absorbing means on the opposite end of said walking beam.
- 10 6. In a compressor, the combination of a fly-wheel and a power wheel, a walking beam and a stationary fulcrum therefor, means operatively connecting said power wheel and the power end of said walking beam, a compressing cylinder provided with a piston rod and plunger, means for applying power to said piston rod consisting of link bars pivotally connected to said walking beam between the power end thereof and said stationary fulcrum and connected to the piston rod of said compressing cylinder, and power absorbing means on the work end of said walking beam operated by said power wheel.
- 15 7. In a compressor, the combination of a power wheel, a pair of walking beams and stationary fulcrums therefor, link bars and cranks operatively connecting said power wheel and the power ends of said walking beams, a compressing cylinder operatively connected to one of said beams and a compressing cylinder operatively connected to the other walking beam, means between the power ends of said beams and said fulcrums operatively connecting said beams to said compressing cylinders, inverted compressing cylinders at the opposite ends of said walking beams from the power ends thereof, and power exerting means operatively connecting the latter compressing cylinders to said opposite ends of said walking beams.
- 20 45 In testimony whereof, I set my hand, this 20th day of October, 1928.

WILLIAM L. DAYTON.
